US0D1059323S

(12) **United States Design Patent** (10) **Patent No.:** **US D1,059,323 S**
(45) **Date of Patent:** ** *Jan. 28, 2025

(54) **ELECTRONIC DEVICE**

(71) Applicant: **Roku, Inc.**, San Jose, CA (US)

(72) Inventors: **Gregory Michael Hogan**, Dublin, CA (US); **Paul Nangeroni**, San Francisco, CA (US); **Fred Bould**, Menlo Park, CA (US); **Jeremy Wolf**, San Francisco, CA (US); **Calvin Patrick Henderson**, Brisbane, CA (US)

(73) Assignee: **ROKU, INC.**, San Jose, CA (US)

(*) Notice: This patent is subject to a terminal disclaimer.

(**) Term: **15 Years**

(21) Appl. No.: **29/894,349**

(22) Filed: **Jun. 8, 2023**

Related U.S. Application Data

(63) Continuation of application No. 29/778,950, filed on Apr. 15, 2021, now Pat. No. Des. 992,523.

(57) **CLAIM**

The ornamental design for an electronic device as shown and described.

DESCRIPTION

FIG. 1 is a top perspective view of an electronic device showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the electronic device that form no part of the claimed design.

1 Claim, 5 Drawing Sheets
